DESIGN FOR A COMBINATION SALT AND PEPPER SHAKER

Roy Gravem, Berkeley, Calif.

Application January 22, 1938, Serial No. 74,479

Term of patent 7 years

To all whom it may concern:

Be it known that I, Roy Gravem, a citizen of the United States, residing in the city of Berkeley, county of Alameda, State of California, have invented a new, original, and ornamental Design for a Combination Salt and Pepper Shaker, of which the following is a specification, reference being had to the accompanying drawing, forming part thereof, in which—

Fig. 1 is a perspective view of a combination salt and pepper shaker showing my design;

Fig. 2 is an end view of one end of the combination salt and pepper shaker;

Fig. 3 is a side elevational view of same;

Fig. 4 is an end view of the opposite end;

Fig. 5 is a top plan view of same.

I claim:

The ornamental design for a combination salt and pepper shaker, as shown.

ROY GRAVEM.
